UNITED STATES PATENT OFFICE.

SAMUEL KLEIN, OF PHILADELPHIA, PENNSYLVANIA.

DESIGN FOR A TOY CAR FOR CHILDREN.

56,438.

Specification for Design.

Patented Oct. 26, 1920.

Application filed May 29, 1920. Serial No. 385,367. Term of patent 7 years.

To all whom it may concern:

Be it known that I, SAMUEL KLEIN, a citizen of the United States, residing in the city of Philadelphia, in the State of Pennsylvania, have invented a new, original, and ornamental Design for a Toy Car for Children, of which the following is a specification, reference being had to the accompany-

ing drawing, forming a part hereof, in which the design is illustrated.

I claim:

The ornamental design for a toy car for children, as shown.

This specification signed this 22d day of May, 1920.

SAMUEL KLEIN.
